UNITED STATES PATENT OFFICE

2,445,600

TENSION DEVICE

Carl O. Bruestle, Rahway, N. J., assignor to Borg-Warner Corporation, Chicago, Ill., a corporation of Illinois

Application December 28, 1944, Serial No. 570,076

14 Claims. (Cl. 140—36)

1
This invention relates generally to weaving machines, but it is more specifically directed to improvements in machines for weaving screen cloth of metal or other material and particularly a screen cloth characterized by ribbon-like wefts that function as louvers, when the screen is in use, to exclude direct sunlight.

After the woven screen is advanced or delivered from the weaving head it is preferably wound in a continuous length in the form of a bundle on a suitable core. The delivery of the cloth from the weaving head is characterized by its intermittent movement. In the present arrangement provision is made to wind the woven screen by intermittently rotating the bundle winding core, and synchronize this step-by-step movement with that of the delivery of the screen from the weaving instrumentalities. Also provision is made for maintaining the cloth under tension to hold it taut between the delivery and winding devices thereby to eliminate slack in the screen and also to prevent distortion or damage to the ribbon-like weft strands that comprise the louvers of the woven screen.

It is one of the principal objects of this invention to simplify the construction of a screen weaving machine such as contemplated herein and to improve the efficiency, operation and dependability of such weaving machine.

Another principal object hereof is to provide means in a screen cloth weaving machine for imparting sufficient tension to the delivered screen cloth to permit such cloth being wound in a bundle without damage thereto especially as respects the louver or ribbon-like weft strands.

A further principal object is to provide tensioning means between a suitable take-off or delivery device and a winding core in a wire screen weaving machine, such tensioning means arranged to absorb any shock to which the screen cloth is subjected that may be due to the intermittent operation of the winding mechanism. In this connection the construction and arrangement of the tensioning means is such as to effect a slippage in the event sudden jerks occur during the feed of the screen cloth to the winding core.

Still another object is to provide a weaving device for producing a screen cloth having ribbon-like weft members, said weaving device having a positive take-off and provision for rolling the

2
woven screen onto a winding core while maintaining proper predetermined tension on the screen to keep it taut between the take-off and the core, thereby to prevent damage to the ribbon-like weft member.

Additional objects, aims and advantages of the invention contemplated herein will be apparent to persons skilled in the art after the construction and operation of the tensioning device is understood from the within description. It is preferred to accomplish the numerous objects of this invention and to practice the same in substantially the manner hereinafter fully described and as more particularly pointed out in the claims. Reference is now made to the accompanying drawings that form a part of this specification, wherein:

Fig. 1 is a front elevation of portions of a screen weaving machine showing the present improvements incorporated thereon;

20 Fig. 1A is a view in perspective showing a fragmentary portion of a screen cloth produced by a weaving machine of the character disclosed herein;

Fig. 2 is a composite vertical section taken 25 along the planes of lines 2—2 and 2a—2a on Fig. 1;

Fig. 3 is a vertical section taken along the plane of line 3—3 on Fig. 2, with parts enlarged and the shaft foreshortened;

30 Fig. 4 is a horizontal fragmentary section along the plane of line 4—4 on Fig. 2, looking down in the direction of the arrows;

Fig. 5 is a vertical elevation viewed on the plane of line 5—5 on Fig. 3; and

35 Fig. 6 is a fragmentary horizontal section taken along the plane of line 6—6 on Fig. 1.

The drawings are to be understood as being more or less of a schematic character for the purpose of disclosing a typical or preferred form of 40 the improvements contemplated herein, and in these drawings like reference characters identify the same parts in the different views.

In the weaving machine shown in Fig. 2, the weaving head at the left-hand portion thereof is 45 a section on line 2a—2a of Fig. 1. Said weaving head comprises the fixed frame 10 having the shelf 12 and the base 14 supported on a standard 16; the comb assembly 18 on said shelf; and suitable driving means exemplified by the rotatable shaft 20. The quill assembly 22 that is carried by

3 shelf 12 is operated by a longitudinally reciprocal horizontal rack 24 which in turn is driven by a rocker arm 26 fulcrumed on the shelf and oscillated by a suitable cam device (not shown) which is keyed to the shaft 20.

The comb assembly 18 is supported on the upper portion of a swinging frame that comprises the upstanding longitudinal wall 28 and irregularly shaped lateral webs 30 having fulcrums on an axle 32 that passes through these webs for journaling the frame for swinging movement as seen in Fig. 2. The comb assembly comprises generally a vertically movable slide member 34 mounted in ways or guides 36 on wall 28 and carries on its upper portion the front comb 38 yieldingly urged toward and against the back comb 40 which is carried in a seat 42 on wall 28. Thus the front comb 38 rides on the back comb 40 and it is movable up and down with respect thereto by reason of the vertical movement of the slide 34. A roller 44 on the adjacent end of an arm 46 operates in a recess 45 in the slide to move the latter, said arm being fulcrumed on a pivot 48 beneath the shelf 12. The other end of arm 46 carries a roller 50 riding on an edge cam 52 having a land 54 and keyed to the driving shaft 20.

A roller 33 carried on the back portions of the frame webs 30 rides on an edge cam 35 on shaft 20 alongside the cam 52, which may be identical with cam 52 and having a land 35a, thus effecting the swinging movement of the supporting frame for intermittently shifting the back comb 40 away from the quills in a horizontal direction to predetermine the spacing of the weft strands and for advancing the woven screen to the take-off and winding devices.

The web or woven fabric produced by the machine is preferably a metal cloth or mesh A which, as shown in perspective in Fig. 1A, comprises spaced ribbon-like weft elements *a* around which warp wires *b* are tied or twisted for maintaining the ribbon-like weft elements in their desired spaced relation. This arrangement provides an insect screen capable of substantially excluding passage therethrough of direct sun rays. After the front comb 38 has moved down to clear the mesh, the back comb 40 moves away from the quills 22 while engaged with the last inserted weft element *a* and draws with it the warp strands sufficiently to properly space the next weft element. The combs are then returned to their operative position for the insertion of the next weft element. It will be seen that the delivery of the woven mesh from the weaving head is intermittent.

The woven screen is advanced to the take-off device where it is trained onto an elongated roller 56, then between this roller and an opposing roller 58, and thereafter the screen is wound in a bundle on a core 60 to which its leading end is suitably attached. The rollers 56 and 58, which are arranged in superposed relation, are made of soft material to prevent damaging the screen, and as seen in Fig. 1 the trunnions of these rollers have meshed gears 62 and 64 secured to them the upper gears 62 being provided with sprockets 66 upon which chains 68 and 70 are trained. The chain 70 is engaged with idle sprocket 72 that directs said chain to sprocket 74 for driving the core 60 of the fabric bundle, and chain 68 is engaged with a sprocket 76 at the adjacent end of a horizontal shaft 78. A sprocket 80 on the other end of shaft 78 is engaged by chain 70 as seen in Fig. 2.

The winding core 60 preferably is tubular and its end nearest sprocket 76 is carried on a plunger-like trunnion 82 the shank of which is slidably mounted in a socket having a double bayonet slot 84 to receive and releasably retain a lateral pin 86 projecting from said trunnion for holding it in retracted or projected positions. By retracting the trunnion 82 its head is removed from the tubular core 60 to facilitate dismounting the 10 bundle as well as ready replacement of a core.

The other end of core 60 is carried on a headed plunger-like trunnion 88 that is rotatable and is arranged for yielding axial movement. As shown in Fig. 6, the trunnion 88 is journaled in anti-friction devices 90 and 91 and has a flange 92 against which a washer 94 is pressed by a spring 96 that is interposed between said washer and the flange 98 of a slip collar 100 keyed on trunnion 84 to rotate therewith and for longitudinal movement thereon. Sprocket 74, which is preferably loose on trunnion 88, has a flange 102 opposing collar flange 98 and there is a friction disc 104 interposed between the confronting faces of these opposed flanges 98 and 102. An elongated spacer 105 surrounds trunnion 88 between the outer anti-friction device 90 and a ball-bearing unit 106 alongside sprocket 74. This arrangement creates sufficient drag or braking action for the sprocket to rotate the trunnion 88 for 20 winding the wire mesh on the core. The sprocket is rotated at a definite speed and as the bundle increases in diameter the peripheral speed of the outer convolution of the bundle is faster in lineal feet per minute than the peripheral speed of the 30 core surface, so that the differential in speed gradually increases the pull upon the woven screen between the take-off and the bundle. This condition automatically equalizes because increase of pull on the screen will cause slippage between the frictionally engaged parts of this assembly. Also the arrangement takes care of and absorbs any sudden jerk or jar that may be incidental to the intermittent movement of the screen during the take-off and winding thereof.

The shaft 78 is preferably comprised of a plurality of sections that are coupled by one-way clutches 108 and 109 with the end sections of the shaft journaled in bearings 110 so that the end regions thereof project beyond said bearings as shown in Fig. 3. The hub of sprocket 76, which is loose on shaft 78, has a wide disc-like flange 112, and a shouldered collar 114 is attached by a lock-screw 116 to the shaft alongside said flange for rotation with the shaft. Driving connection between collar 114 and hub flange 112 is effected by a suitable clock spring 118. The outer coil of this spring is looped around a pin 120 projecting laterally from the marginal portion of the hub flange, and the inner coil of spring 118 is bent into a radial slot 122 in the reduced portion of collar 114 as seen in Figs. 3 and 5. The hub of the other sprocket 80 is loose on the adjacent end section of shaft 78 and has a disc-like flange 124 to which the outer coil of a clock spring 126 is attached by a pin 128. The inner coil of this second spring (not shown) is attached to the reduced portion of the shouldered collar 130 that is anchored to shaft 78 by a lock pin 132, thus providing a driving connection between shaft 78 and the sprocket 80.

The shaft 78 is intermittently rotated in synchronized relation with respect to movement of back comb 40 away from the quill head when it draws the warp through the quills and advances 75 the finished web A toward take-off roller 56. To

accomplish this, one of the members of one-way clutch 109 is secured to shaft 78 and the other member which is adapted for reciprocatory rotative movement with respect thereto is connected to a radially projecting arm 134. A pitman bar 136 is fulcrumed for swinging movement on a pivot 138 on arm 134 (Fig. 3) and extends upwardly in an inclined direction (Fig. 2) with its upper end carried upon a crank pin 140 on the exterior of a plate 142 that is bolted to the end of the hollow hub 144 of a gear 146 as shown in Fig. 4. This gear 146 is meshed with a pinion 148 on the adjacent end of shaft 20 so that it is intermittently rotated thereby to turn the crank pin 140. A headed spindle 150, attached to and projecting from the boss 152 of a suitable bracket 154, extends through the gear hub 144, and anti-friction devices 156 interposed between the hub and spindle provide a journal for gear 146. The pivot pin 138 on arm 134 for the lower end of pitman bar 136 is preferably carried by a slide block (not shown) that is adapted for adjustment by a hand wheel 158 in directions longitudinally of arm 134 or radially with respect to shaft 78, thus selectively predetermining the amount of swing that is imparted to arm 134 by pitman bar 136 and the intermittent rotation of shaft 78.

An indicating device, shown at the right hand end of Fig. 3, and detailed in Fig. 5, is employed in order that the operator may readily ascertain whether or not a constant tension is being maintained during the weaving of the screen. This device comprises a pointer 160 projecting radially from the end of shaft 78 for cooperation at its outer end with an L-shaped member 162 anchored to the adjacent portion of the disc-like flange 112. Pointer 160, which preferably has a Z-shape, is adjustably attached to the end of shaft 78 by a suitable clamping screw 164 to permit resetting of the pointer for cooperation with member 162 after tension has been adjusted preparatory to starting the machine. Desired tension is attained by uncoupling pitman bar 136 from pivot 138 and then reciprocating the radial arm 134 until spring 118 is under the required tension, after which pitman bar 136 is recoupled and a final adjustment may be made through hand wheel 158. The pointer 160 is then adjusted to a position alongside its cooperating fixed member 162.

When the weaving machine is operating, the weaving is quite rapid and the outward movement of the back comb 48 away from the quills 22 of the weaving head and its return to the head may require only a fractional portion of a second of time, so this reciprocatory motion is of a rapid vibratory character. During each vibratory movement of the back comb, the take-off and winding assemblies have each been advanced a small segment of a rotation the lineal dimension of which corresponds to the distance the back comb has traveled away from the weaving head to space the ribbon-like weft strands. This vibratory action of the back comb and the rapid intermittent actuation of the take-off and winding assemblies, would ordinarily create either slack in the woven screen or too much pull thereon both of which, it has been found, tend to mar the screen. The present arrangement prevents either of these contingencies arising and is effective constantly in maintaining predetermined tension to avoid injury to the woven screen.

While this invention has been described in detail in its present preferred form or embodiment, it will be apparent to persons skilled in the art,

after understanding the improvements, that various changes and modifications may be made therein without departing from the spirit or scope thereof. It is aimed in the appended claims to cover all such changes and modifications.

I claim:

1. In a weaving device having a weaving head for producing woven screen cloth with ribbon-like weft members; the improvement of means for rolling the woven screen onto a winding core and maintaining proper preselected tension on the woven screen, said means comprising in combination, a winding core; take-off means receiving the screen delivered from said weaving head, the screen being fastened to said core; a driven shaft; sprockets on said driven shaft, said take-off means, and said core; means comprising a chain driving said sprockets in synchronism; friction clutch means providing a driving connection between said core and the sprocket thereon, said clutch means also effecting slippage during overdrive of said sprocket; and yieldable tension means providing a driving connection between said driven shaft and the sprocket thereon.
2. In a weaving device having a weaving head for producing woven screen cloth with ribbon-like weft members; the improvement of means for rolling the woven screen onto a winding core and maintaining proper preselected tension on the woven screen, said means comprising in combination, a winding core; a take-off roll receiving the woven screen delivered from said weaving head, the screen being fastened to said core; a driven shaft; a one-way drive clutch on said shaft; means for operating said clutch to impart intermittent rotation to said shaft; a sprocket loose on said shaft; tension means effecting a yieldable driving connection between said shaft and the sprocket thereon; sprockets on take-off roll, and said core; means comprising a chain driving all of said sprockets in synchronism; and friction clutch means providing a driving connection between said core and the sprocket thereon and adapted to effect slippage during any overdrive of said sprocket.
3. In a weaving machine having a weaving head for producing a screen, a comb adapted for reciprocable movement away from the weaving head to longitudinally advance the screen a distance for effecting the spacing of the weft strands of the screen; take-off means comprising take-off rollers for withdrawing the screen from said comb; a rotatable core for winding the screen; and common driving means for actuating said comb and for rotating said rollers and core, said driving means including a frictional slip device whereby said driving means is effective to wind a length of screen on said core that is at least approximately equal to the length of screen advanced away from the weaving head by said comb.
4. In a weaving machine having a weaving head for producing a woven screen, a movable comb assembly including a comb and a reciprocable support for moving the comb to longitudinally advance the screen away from the weaving head a distance for predetermining the spacing of the weft strands of the screen; take-off means comprising take-off rollers for withdrawing the screen from said comb; a rotatable screen bundle winding core for receiving the screen withdrawn by said rollers; and common driving means for actuating said comb assembly and for rotating said rollers and core, said driving means including a frictional slip device

whereby said driving means is effective to wind a length of screen on said core that approximates to the length of screen advanced by said comb assembly and to maintain in a taut condition the portion of the screen between the bundle and the weaving head.

5. In a weaving device having a weaving head for producing woven screen cloth, the improvement of means for rolling the woven screen onto a winding core and maintaining proper tension on the woven screen, said means comprising a reciprocable comb coacting with the weaving head and movable to advance the woven screen away from said weaving head; take-off means receiving the woven screen advanced by said comb; a rotatable core for winding the woven screen from said take-off means; and common driving means for rotating said take-off means and core and for actuating said comb, said last-mentioned means including a frictional slip device whereby said means is effective for maintaining the woven screen under tension between said comb and said core.

6. In a weaving device having a weaving head for producing woven screen-cloth having ribbon-like weft members; the improvement of means for rolling the woven screen onto a winding core and maintaining proper preselected tension on the woven screen, said means comprising in combination, a winding core; opposing take-off rolls receiving the woven screen delivered from said weaving head, the screen being threaded through said take-off rolls and fastened to said core; a driven shaft; driving means on said take-off rolls, and said core, said driving means having operative connection with and actuated by said driven shaft; endless means for rotating all of said driving means in synchronism; means for intermittently rotating said driven shaft whereby to transmit intermittent motion through said endless means to said take-off rolls and said core, and yieldable tension means providing a driving connection between driven shaft and the driving means thereon.

7. In a machine for weaving a screen having louver-like weft strands, a comb support; means for reciprocating said support in a direction to move the screen away from the weaving head of the machine; a take-off winding assembly including a rotatable core for winding the screen; and common driving means for rotating said take-off winding means and for actuating said support reciprocating means, the construction and arrangement of said common driving means being such that the screen is maintained under constant tension between said comb support and said core.

8. In a machine for weaving a screen having louver-like weft strands, said machine having a weaving head including a vibratory comb member; a take-off roller; actuator means for effecting said vibration of the comb member to advance the woven screen to said take-off roller; a rotatable core for winding the screen from said take-off roller; and means for driving said take-off roller and core from said comb actuator means, said driving means including driven members individual to and drivingly connecting said roller and core for simultaneous rotation; a friction clutch assembly effecting an operative connection between said core and the driven member individual thereto; and a driven shaft rotated by said actuator means, said shaft having driving connection with the individual driven members for said take-off roller and said core.

9. In a machine for weaving a screen as defined in claim 8, wherein the driving means includes one-way clutch means interposed between the driven shaft and the actuator means for effecting intermittent rotation of the driven shaft, the take-off roller and the core.

10. In a weaving machine having a weaving head for producing a woven screen with ribbon-like weft members, the said head including a vibratory comb adapted to advance the woven screen away from the head, a continuously rotatable driving shaft; a support for the comb fulcrumed for vibratory movement; cam means on said driving shaft for effecting the aforesaid vibratory movement of said support; a countershaft; a one-way clutch device one member of which is anchored to said countershaft; a crank element continuously rotated by said driving shaft; a pitman operatively connecting said crank element and the other one-way clutch member for effecting intermittent rotation of said countershaft; roller means constituting a take-off for the woven screen advanced from the weaving head; a core for winding the woven screen received from said take-off; and devices effecting a driving connection between said countershaft, said take-off rollers, and said core.

11. A weaving machine arrangement as defined in claim 10 wherein the devices for effecting a driving connection between the countershaft, the take-off and the core comprise a chain; sprockets on the shaft, the take-off and the core; and means effective for maintaining predetermined tension on the woven screen between the weaving head and the winding core.

12. A weaving machine arrangement as defined in claim 10 wherein the devices for effecting a driving connection between the countershaft, the take-off and the core comprise rotatable members individual the countershaft, the take-off and the core; an endless element drivingly engaged with said individual members for simultaneously rotating the members on said take-off and said core in synchronized relation to the member individual to the countershaft; and yieldable means interposed between and operatively connecting the countershaft to the rotatable member individual thereto.

13. In a weaving device, a weaving head for producing woven screen cloth with ribbonlike weft members; means for rolling the woven screen on a winding core and maintaining proper preselected tension on the woven screen, said means comprising in combination, a winding core; a plurality of take-off rolls for withdrawing the screen from the weaving head and advancing the screen to said core; a rotatable shaft; driving means operatively connecting said core and take-off rolls to said shaft; friction clutch means connecting said core and driving means for effecting a slip driving connection for said core; and tension creating means between said shaft and the means for driving said core.

14. In a weaving device having a weaving head for producing woven screen-cloth with ribbon-like weft strands; said head having a reciprocable comb; the improvement of means for rolling the woven screen onto a winding core and maintaining proper preselected tension on the woven screen, said means comprising in combination, a winding core; opposed take-off rolls for withdrawing the woven screen from said weaving head and advancing the screen to said core; a rotatable shaft; sprockets on said shaft, said take-off rolls and said core; chain means driven by said

shaft sprocket for rotating the take-off and core sprockets in synchronism with said shaft sprocket; means operative to actuate said shaft in synchronism with said comb for intermittently rotating said shaft, whereby intermittent motion is transmitted through said chain and sprockets to said take-off rolls and said core; and tension means providing a frictional driving connection between rotatable shaft and the sprocket thereon.

CARL O. BRUESTLE.
